UNITED STATES PATENT OFFICE

105,695

DESIGN FOR A MAN'S CONFINING BELT

George L. Diebold, Chicago, Ill., assignor to Venus Foundation Garments, Inc., Chicago, Ill., a corporation of Delaware

Application May 3, 1937, Serial No. 69,132

Term of patent 7 years

To all whom it may concern:

Be it known that I, George L. Diebold, a citizen of the United States, residing at Chicago, in the county of Cook and State of Illinois, have invented a new, original, and ornamental Design for a Man's Confining Belt, of which the following is a specification, reference being had to the accompanying drawing, wherein—

Fig. 2 is a perspective of the rear thereof.

I claim:

The ornamental design for a man's confining belt, as shown.

GEORGE L. DIEBOLD.
